UNITED STATES PATENT OFFICE.

TITUS ANDREW BEECHER, OF TAFT, CALIFORNIA.

ATTACHMENT FOR ROTARY WELL-BITS.

1,118,726.

Specification of Letters Patent.

Patented Nov. 24, 1914.

Application filed March 19, 1913. Serial No. 755,372.

To all whom it may concern:

Be it known that I, TITUS A. BEECHER, a citizen of the United States, and a resident of Taft, in the county of Kern and State of California, have invented a new and Improved Attachment for Rotary Well-Bits, of which the following is a full, clear, and exact description.

This invention relates to improvements in 10 attachments for well drills, and particularly to a safety device designed to recover lost rotary bits, and has for an object to provide an improved structure which will not only hold the lost or broken off portion so that 15 the same may be withdrawn, but will cause an indication at the surface showing that the bit is broken or lost.

A further object of the invention is to provide a controlling valve for shutting off 20 the flow of water from the circulating pump when a bit is broken off and thereby indicate what has occurred at the bottom of the well.

In carrying out the objects of the invention, a flexible cable is connected to the bit 25 and to a movably or adjustably secured member associated with the valve which shuts the water off from a circulating pump. This construction permits the bit when broken off to hold the lower end of the cable stationary 30 while the upper end connected with the valve is rotated, and by such twisting action to shorten the cable, resulting in a downward and closing movement of the valve. This will indicate to the operator that the bit 35 has broken off so that he may take proper steps to remove the broken drill and substitute a new one.

A practical embodiment of the invention is represented in the accompanying drawings 40 forming a part of this specification, in which similar characters of reference indicate corresponding parts in all the views.

Figure 1 is a longitudinal vertical section through the upper part of the structure 45 shown in Fig. 4, the same showing the action when the bit is broken off; Fig. 2 is a section through Fig. 1 on the line 2—2; Fig. 3 is a section through Fig. 1 on the line 3—3; Fig. 4 is a longitudinal vertical section through 50 an embodiment of the invention previous to the breaking of the bit; and Fig. 5 is a fragmentary sectional view showing the connection between the valve rod and the draw rod.

Referring to the accompanying drawings 55 by numerals, 1 indicates a well, and 2 the usual tubing provided. Connected to the

lower end of the tubing 2, is a bit 3 having a cutting portion 4 and a retaining threaded conical-shaped portion 5 fitting into a threaded conical-shaped opening in a member 6 rigidly secured to the tubing 2. The bit 3 is provided with a pair of openings 7 through which the water may circulate when the device is operating properly. The bit 3 is provided with an aperture 8 arranged 60 centrally thereof, having an enlargement 9 at the end so that when the Babbitt metal 10 is placed in position around the cable 11, the same will be interlocked or wedged in place. The Babbitt metal is preferably 65 melted, and while in a molten state, is poured in place. The cable 11 has secured at its upper end a connecting member 12 which is secured to the connecting member 13 by being threaded therein. It will be 70 evident that the members 12 and 13 could be coupled together in any other desired way which would positively hold the same in engagement during the rotation of the device, and especially during the rotation of the 75 device after the bit 3 had broken off. Connected to the member 13 is a cable 14 extending upwardly and into a socket 15 in the end of a squared reciprocating shaft 16, where it is secured by Babbitt metal which is 80 preferably placed in position as above indicated while in a molten state, whereby the cable is rigidly clamped or braced in position. The shaft 16 is preferably formed square and loosely fits in the squared portion 17 of 85 the valve 18, whereby the valve may be adjusted back and forth freely. The upper end of the shaft 16 is threaded at 19 and accommodates nuts 20 which are designed to regulate the position of the valve 18. If for any 90 cause whatever the bit 3 should break off the same will remain stationary while the tube or pipe 2 will continue to rotate. This will cause a twisting or winding of the cables 11 and 14 substantially as shown in Fig. 4, 100 which will naturally shorten the same and cause a downward movement of the valve 18 until the same enters the passageway 21, whereupon the water will be shut off from the circulating pump. This will be a notification to the operator that the bit has 105 broken off and is remaining stationary. In constructing the valve 18, the same is formed with projections 23 and 24 slidably fitted into slots 25 and 26, as more clearly shown 110 in Fig. 2, so that the valve is given a free up and down movement and not a rotary

movement, so that when the cables 11 and 14 twist the same cannot turn the valve.

The upper end of the tube or casing 2 may be arranged in any desired manner, and 5 also have any desired driving and lifting means associated therewith, the construction of the means for rotating the casing, and the means for raising and lowering the same not forming any part of the invention.

10 The invention consists in means for indicating that the bit has broken off, the same including a valve 18, part of a bit 3, and the cables and other connecting mechanism between the bit and the valve.

15 Having thus described my invention, I claim as new and desire to secure by Letters Patent:

1. In a device of the character described, the combination with a well casing including 20 a bit, of a water controlling valve, and a flexible member connecting said valve with said bit adapted to be shortened by twisting, whereby whenever said bit is broken off, a longitudinal movement will be given said 25 valve for closing the same.

2. In a device of the character described, the combination with a well casing provided with a valve, of a flexible cable connected at one end to said valve and at the other end 30 to said bit so as to rotate with the casing and associated devices when the bit is in proper operation, said cable being adapted to be twisted and thereby shortened when said bit is broken from the casing and the 35 casing is given a continued rotary movement, the shortening of said cable causing the closing of said valve whereby water flowing through the valve will be cut off.

3. In a device of the character described, 40 the combination with a casing provided with a bit, of a reciprocating valve designed to control the water as the same passes into the casing, means for limiting the motion of the valve to a reciprocatory motion, and 45 a cable connected at one end to said valve and at the other end to said bit, whereby when said bit is broken from the casing and the casing and valve carried thereby are rotated, the cable will be twisted and consequently shortened for causing a longitudinal 50 movement of said valve for closing the same.

4. In a device of the character described, the combination with a rotary well casing, 55 of a reciprocating valve arranged therein, resilient means for normally holding said valve open, a cable connected with said valve at one end, and means for connecting the opposite end of said cable to the bit as-

sociated with said casing, said cable being 60 adapted to be twisted and thereby shortened when said bit is broken from the casing and the casing is rotated, the shortening of said cable causing a longitudinal action of said valve and the consequent closing thereof. 65

5. In a device of the character described, the combination with a rotary casing provided with a bit, of a flexible member connected with said bit and adapted to be shortened by twisting, and means connected 70 with and actuated by the flexible member for indicating that the casing is moving independently of the bit.

6. In a device of the character described, the combination with a rotary casing having 75 a bit at the lower end, of a contractible member connected with said bit and a reciprocating valve arranged at any desired point in the casing secured to the upper end of said contractible member whereby when 80 said bit is broken off said contractible member will be operated upon the continuous rotation of the casing and valve independent of the bit, whereby a downward pull on the valve will be caused for closing the same. 85

7. In a device of the character described, the combination with a rotary casing having a bit rigidly secured thereto at the lower end, of a valve arranged in said casing, guideways for said valve for causing the 90 same to rotate with the casing while being permitted a longitudinal reciprocatory movement, means for holding said valve normally open, and a contractible member secured at one end to said valve and at the 95 other end to said bit whereby when said bit is broken off and is held stationary while the casing is rotated, said contractible member will be contracted and give said valve a longitudinal movement until the same is 100 closed.

8. In a device of the character described, the combination with a rotary well casing, of a valve mounted to rotate with said casing and having guided reciprocating movement therein, means for normally holding said valve open, a shaft connected with said valve, a bit at the lower end of the casing, and a flexible cable connecting the lower end 105 of said shaft with the said bit. 110

In testimony whereof I have signed my name to this specification in the presence of two subscribing witnesses.

TITUS ANDREW BEECHER.
